R. L. OWENS.
GRAIN SEPARATOR.
APPLICATION FILED NOV. 18, 1921.
1,422,298.

Patented July 11, 1922.

UNITED STATES PATENT OFFICE.

RICHARD L. OWENS, OF MINNEAPOLIS, MINNESOTA.

GRAIN SEPARATOR.

1,422,298.

Specification of Letters Patent. Patented July 11, 1922.

Original application filed December 12, 1917, Serial No. 206,783. Divided and this application filed November 18, 1921. Serial No. 516,137.

To all whom it may concern:

Be it known that I, RICHARD L. OWENS, citizen of the United States, resident of Minneapolis, in the county of Hennepin and 5 State of Minnesota, have invented certain new and useful Improvements in Grain Separators, of which the following is a specification.

In an application for patent filed by me 10 on December 12th, 1917, Serial No. 206,783, I have shown and described a grain separator, the primary object of which is to provide means in connection with the upper gang of sieves for removing or separating from the 15 stream of grain the clean wheat or other grain, which has fallen through the upper portion of the screen, in the upper gang, and directing this clean grain out of the machine at the point where it falls through the screen.

20 My present invention is a modification of the principal structure disclosed in my said application, and my present application is a division of the application above referred to.

In the invention described herein I provide 25 a single upper gang of sieves, with means for feeding the grain to be cleaned or separated to the upper end of said gang, the clean wheat, or other grain, passing directly through the upper portions of the screen and 30 being preferably taken directly out of the machine at the point where it falls through the lowermost screen.

The invention consists generally in various 35 constructions and combinations all as herein-after described and particularly pointed out in the claims.

In the accompanying drawings forming part of this specification,

Figure 1 is a longitudinal vertical section 40 of the machine,

Figure 2 is a detail plan of a portion of the lower deck and discharge spout,

Figure 3 is a vertical section on the line 3—3 of Figure 2, looking in the direction of 45 the arrows,

In the drawings, 2 represents the frame of the machine which may be of any suitable size, and is provided with the usual fan 3 within a casing 4. 5 represents a shoe in 50 which a series of sieves 6 are mounted. The machine is provided with a hopper 7 into which the grain to be cleaned is delivered. From the hopper the grain passes through a discharge opening 8, having a cut-off valve 55 9 provided with an operating rod 10, and be-

low the opening 8 is a chamber 11 in which a feed roll 12 is arranged. Gates 13 are pivoted at 14 and slidably connected at 15 with an operating lever 16, which is pivoted at 17 and has adjusting means at 18 for setting the gates 13 in the desired position with respect to the opening 8. These gates are free to rock, but are counterweighted to normally overcome the pressure of the material. In case, however, any foreign article 60 of comparatively large size should be mixed with the grain it will raise the gates and not clog the passage. The chamber 11 is connected through a throat or passage 19 with a fan 20 within a casing 21, and a valve 22 65 is provided in the chamber 11, for regulating the width of the passage between the feed roll 12 and the wall of the chamber. A slide 23 is preferably provided above the fan casing 21, operable by a rod 24, and in the bottom of the passage 19 a screw conveyer 25 is 70 preferably mounted. Beneath the chamber 11 is a sieve 26 whereon the material from the hopper is delivered, the light refuse or tailings passing down over the sieve through a 75 spout 27, while the grain is delivered upon the sieves of the gang beneath, the delivery being regulated by the gates 13. By the mechanism described provision is made for controlling the strength of the air current 80 through the feed chamber according to the condition and character of the grain to be 85 cleaned.

I make no claim in this application to the 90 hopper and feed mechanism arranged in connection therewith, as the same has been claimed by me in applications now pending in the United States Patent Office, No. 208,577, filed December 24th, 1917, and No. 278,446, filed February 24th, 1919.

The shoe 5 is supported by suitable hangers and is capable of either a sidewise shaking or a longitudinally oscillating movement, or both. These hangers, however, may be of any suitable or preferred construction, and 95 are common to machines of this type. I have not thought it necessary, therefore, to illustrate the shoe supporting and oscillating means in this application.

The upper end of the shoe 5 is preferably 100 arranged directly below a scalping sieve 26 which intercepts and carries away the straw and other coarse material. A plate or deck 28 beneath the scalping sieve receives the grain falling therethrough. This deck ex- 110

tends substantially parallel with the sieve 26, and has the function of directing the grain in a thin sheet upon the deck 29 beneath. The deck 28 is preferably provided 5 near its lower or discharge end with a depressed and substantially horizontal portion 28' from which the grain is fed to the deck of the sieve below. The shape of this portion of the deck tends to slow up the travel 10 of the grain and cause it to flow evenly in a thin sheet onto the deck 29 of the upper sieve of the shoe 5.

The shoe 5 is provided as hereinbefore stated with a series of sieves 6 arranged to 15 overlap each other, and each is so located as to carry forward the grain received from the sieve next above in the gang. Under the upper part of the lower sieve 6 of this gang I provide a transverse spout 30 to 20 receive the clean wheat, or other grain, which has fallen upon the upper portion of each sieve 6 and has passed through the meshes thereof, and to conduct such clean wheat or other grain out of the machine.

25 The separation takes place in this way: Suppose that a sheet of grain is delivered to the upper sieve of the gang 5, and the wheat kernels, being heavier than the oats, or the weed seeds, and other like refuse material, 30 will naturally work to the bottom of the sheet of material, which may be several inches in depth. It is evident that the kernels at the bottom of the sheet on the upper sieve will pass through the upper portions 35 of the meshes of that sieve, and then on through the upper portion of the meshes of each following sieve until the bottom of the gang is reached, when such clean grain will fall into the spout 30 and be conducted out of the machine. Provision thus 40 being made for removing this mass of clean grain falling through the upper portion of the sieves of the gang 5, the separation will be effected much quicker and the capacity 45 of the machine will be greatly increased.

Arranged above the down-sieve side of the spout 30 is a movable deck or slide 31, provided with a rack 32, engaged by a pinion 33 on a shaft 34. By rotating the shaft 34 50 the deck 31 may be moved to cover the spout 30 to a greater or less extent, thereby regulating the amount of grain that falls into said spout.

The grain that tails over all of the sieves 55 6 falls into a transverse spout 40, and is, thereby, directed to a suitable discharge point. The grain that passes through the lower sieve 6 below the upper edge of the deck 31, when said deck overlaps the spout 30, falls partly upon a deck 36 by which it is conducted to a transverse repeat spout 42 or upon a movable board or slide 43, having a rack 39 and engaged by a pinion 44 upon a shaft 41. This board conducts the 60 grain that falls upon it to an oppositely in-

clined sieve 45, beneath which is a deck 50, that discharges into a spout 51. The position of the board 43 determines the amount of grain that falls upon the deck 36, and hence the amount that goes to the repeat 70 elevator. This board is, therefore, designated as the "repeat board." Above the screen 45 I preferably arrange an inclined deck 48 and screen 46. As an obvious modification the repeat board 43 may discharge 75 onto the upper screen 46 instead of the lower screen 45. A spout 47 is provided for receiving the material that tails over both of the screens 45 and 46 and a transverse or inclined cleat or dam 49 (Figure 2) is provided at the lower end of the deck 48, causing the material passing along said deck to be conducted through ducts 49' into the spout 41 where it mingles with the material passing over the deck 50 (Figures 2 and 3). 80 The screenings from the separations made by the sieves 45 and 46 are preferably received and mixed in the spout 51, while the clean products from both separations made by said screens are preferably received and 85 mixed in the transverse spouts 47.

I may provide suitable adjustable supporting means for the spout 30 so that the same may be adjusted lengthwise of the shoe 5 as indicated by the double-pointed arrow in 95 Figure 1, thereby increasing or decreasing the space beneath the upper portion of the lower sieve 6 that will be occupied by said spout.

When the spout 30 and deck 31 are in the 100 position shown in Figure 1 the grain passing through the upper part of the lower sieve 6 will fall directly into the spout 30 and be conducted out of the machine. By adjusting the deck 31 towards the lower end of the 105 lower screen 6 a space may be left between the wall of the spout 30 and the upper edge of the deck 31, and a portion of the grain will then fall between the spout 30 and the deck 31 upon the deck 46' of the screen 46. 110 This space may be increased by adjusting the spout 30 laterally towards the fan 3.

The material from the repeat spout 42 passes to a repeat elevator 52 which elevates it to a spout 53 for delivery to spouts 54 and 115 55, the latter delivering the material to the upper sieve 6 either directly or by means of an interposed deck 55. This material is then conducted through or over the sieves 6 for a 120 second separation.

In the operation of the machine the grain is fed out of the hopper onto the scalping sieve beneath, the straw and coarse material being removed by said scalping screen, and the partially screened grain allowed to fall 125 through this scalping sieve upon the upper sieve 6 of the gang. The heavier kernels, such as wheat, working to the bottom of the sieve will fall through the upper portions of the sieves, and, dropping into the spout 30, 130

- will be taken out of the machine, and further travel of this grain on the sieves will be eliminated. The cleaning of the grain will thereby be hastened and the capacity of the 5 machine considerably increased. The remainder of the material will pass down through and over the sieves, the tailings of all the sieves passing to the spout 40, and the repeat elevator receiving and returning to 10 the upper sieve 6, a considerable portion of the material which has fallen through the lower sieve 6. The final separation of a portion of the material falling through the lower sieve 6 beyond the spout 30 is made by the 15 screens 45 and 46, mounted in the lower portion of the machine, and from which the grain may be spouted in a thoroughly separated or cleaned condition.
- By adjusting the spout 30 towards the fan 20 sufficiently so that it does not receive any grain from the lower sieve 6, or by removing this spout altogether, the grain falling through the upper portion of the lower sieve 6 will be received directly upon the sieve 25 46 and its deck 46', and the deck 31 and repeat board 43 may then be adjusted so as to conduct a part of the remaining grain falling through the lower sieve 6, to the screen 45, or all of this grain may, by suitable adjustment of said deck and repeat board be conducted to the deck and the repeat spout 42.
- I claim as my invention:
1. In a grain cleaning machine, the combination, with a grain delivering hopper, 35 of a plurality of sieves arranged in an inclined gang, means for delivering the grain in a sheet upon the upper sieve of the gang, and passing through and over the sieves of the gang, an oppositely inclined screen arranged beneath the upper portion of the lower sieve of the gang, an inclined deck arranged beneath the lower portion of said lower sieve, a repeat elevator arranged to receive material from said inclined deck, 40 and an adjustable repeat board arranged to selectively divide the material passing through the lower portion of the lower sieve of said gang between said repeat spout and the oppositely inclined screen.
  2. In a grain cleaning machine, the combination with the grain delivering hopper, 45 of a plurality of sieves arranged in an inclined gang, means for delivering the grain in a sheet upon the upper sieve of the gang, and passing through and over the sieves of the gang, an oppositely inclined screen arranged beneath the upper portion of the lower sieve of the gang, an inclined deck arranged beneath the lower portion of said 50 lower sieve, a fan arranged to discharge into the space between said gang and said oppositely inclined screen, a repeat elevator arranged to receive material from said inclined deck, and an adjustable repeat board arranged to selectively divide the material 65 passing through the lower portion of the lower sieve of said gang between said repeat spout and said oppositely inclined screen.
  3. In a grain cleaning machine, in combination with the grain delivering hopper, a gang of sieves, means for delivering the grain in a sheet upon the upper sieve of the gang, and passing through and over the sieves of said gang, a quantity of comparatively clean grain passing through the upper portion of each sieve of the gang, a transverse spout mounted beneath the upper portion of the lower sieve of the gang for receiving such comparatively clean grain 80 and conducting it directly out of the machine and an adjustable deck arranged beneath the lower sieve on the down-sieve side of said spout.
  4. In a grain cleaning machine, in combination, with the grain delivering hopper, a gang of sieves, means for delivering the grain in a sheet upon the upper sieve of the gang, and passing through and over the sieves of said gang, a quantity of comparatively clean grain passing through the upper portion of each sieve of the gang, means for receiving such comparatively clean grain and conducting it out of the machine, and means for selectively dividing the grain 95 passing through the remaining portion of the lower sieve of the gang and sending a portion thereof to a re-cleaning screen and a portion thereof to a repeat elevator.
  5. In a grain cleaning machine, in combination with the grain delivering hopper, a gang of sieves, means for delivering the grain in a sheet upon the upper sieve of the gang, and passing through and over the sieves of said gang, a quantity of comparatively clean grain passing through the upper portion of each sieve of the gang, means mounted beneath the upper portion of the lower sieve of the gang for receiving such comparatively clean grain and 100 conducting it directly out of the machine, and means for selectively dividing the grain passing through the remaining portion of the lower sieve of the gang, and sending a portion thereof to a re-cleaning screen, 110 and a portion thereof to a repeat elevator.
- In witness whereof, I have hereunto set my hand this 16" day of November, 1921.

RICHARD L. OWENS.
